UNITED STATES PATENT OFFICE.

ISAAC O. VAN DUZER, OF NEW YORK, N. Y.

DESIGN FOR A COVERING FOR BOXES OR BOOKS.

42,410.

Specification for Design.

Patented Apr. 16, 1912.

Application filed December 14, 1911. Serial No. 665,816. Term of patent 7 years.

To all whom it may concern:

Be it known that I, ISAAC O. VAN DUZER, a citizen of the United States of America, residing in New York, borough of Richmond, in the county of Richmond and State of New York, have invented a certain new, original, and ornamental Design in a Covering for Boxes or Books, of which the following is a specification.

This invention has for its object to provide an improved design for embossed box and book coverings, and more particularly to arrange different cardinal surfaces so as to produce different effects on the eye.

In the accompanying drawing, Figure 1 is a plan view of my improved design, and Fig. 2 is an end-view of the same.

I claim:

The ornamental design for a covering for boxes or books herein shown and described.

In witness whereof, I have hereunto set my hand, this 23rd day of November, 1911.

ISAAC O. VAN DUZER.

In presence of—

JOHN MURTAGH,
L. J. MURPHY.
